OR 0 12,198

No. 12,198

March 29, 1881

UNITED STATES PATENT OFFICE.

GEORGE W. GILL, OF COLUMBUS, OHIO.

DESIGN FOR A COOKING-STOVE.

SPECIFICATION forming part of Design No. 12,198, dated March 29, 1881.

Application filed January 29, 1881. Term of patent 7 years.

To all whom it may concern:

Be it known that I, GEORGE W. GILL, a citizen of the United States, residing at Columbus, in the county of Franklin and State of Ohio, have invented and produced a new and useful Design for Cooking-Stoves; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 One part of this invention consists of the design of the depressed ornamentations A, B, C, D, and E in the oven-door.

Another part consists of the design of the depressed ornamentation in the door F of the auxiliary oven, and in the panel G of the water-heater above said oven.

Another part consists in the design of the depressed ornamentations in the side door, H, of the fire-box.

25 Another part consists in the design of the depressed ornamentations in the front fire-box door, I, and in the projecting plate I' above it.

Another part consists in the design of the depressed ornamentations on the hinges of the 30 doors A and H.

The print or engraving accompanying this specification I hereby declare gives and conveys to any one skilled in the art of stove-making a more definite and thorough description and knowledge of my invention than it is 35 in my power to convey by words, and is sufficient to enable any one skilled in the art to which it pertains to use my invention.

What I claim as my invention is—

1. The configuration of the design for the 40 depressed ornamentations A, B, C, D, and E in the oven-door, they being as shown.

2. The configuration of the design for the depressed ornamentation in the door F, they being as shown.

3. The configuration of the design for the 45 depressed ornamentation of side door, H, of the fire-box, it being as shown.

4. The configuration of the design of the depressed ornamentation in the panel G, it 50 being as shown.

5. The configuration of the design of the depressed ornamentation of the hinge of the oven-door, it being as shown.

In testimony whereof I affix my signature 55 in presence of two witnesses.

GEORGE W. GILL.

Witnesses:

LUTHER WILLIAMS,
CHAS. S. REYNOLDS.
